United States Patent Office.

SAMPSON POPE, OF COVINGTON COUNTY, MISSISSIPPI.

Letters Patent No. 101,160, dated March 22, 1870.

IMPROVED EARTH-AUGER.

The Schedule referred to in these Letters Patent and making part of the same

To all whom it may concern:

Be it known that I, SAMPSON POPE, of the county of Covington, in the State of Mississippi, have invented a new and improved Auger for Boring Well or Post-Holes; and I do hereby declare that the following is a full, clear, and exact description of the construction and operation of the same, reference being had to the accompanying drawings making a part of this specification, in which—

Figure 1 is a side elevation.

Figure 2 is a sectional view.

Figure 3 is a bottom view.

Like letters in the different figures of the drawings indicate like parts.

My invention has reference to the class of augers for boring wells or post-holes, in which the cutters or bits may be detached and sharpened when dull, and consists of two curved cutters or bits arranged at an incline on the inside of the cylinder, in combination with the plates or braces forming the bottom or bucket thereof, so as to enable the cutters to scoop up the dirt more advantageously, the curve and incline of the cutters being such with the sides of the cylinder, while revolving or being operated, that all the dirt scooped up, or fine sand met with in boring, will be retained therein until the cylinder is full enough to be emptied of it.

To enable others skilled in the art to make and use my invention, I will proceed to describe its construction and operation.

A is the cylinder of the proper diameter and height, and having two upright pieces *a a* attached centrally to the sides at the upper end thereof, and a cross-piece, *b*, suitably secured at the top end of each of them.

In the center of the cross-piece a hole is made to receive the shaft *c*, which will be inserted there-

through and rigidly secured, and have an arm attached to the head of it crosswise, so that the cylinder or auger may be turned or operated.

The bottom of the cylinder on each side of it is formed with a cutting-edge, *d*.

Triangular plates or braces *e e* are attached to the bottom edge of the cylinder, next to the cutting-edges *d d*. They incline and nearly meet at the center of the cylinder.

To these plates or braces *e e*, and to the sides of the cylinder, on the inside thereof, are attached the curved cutters or bits *g*. Each cutter being of the width of one side of the plate or brace, and inclining up therefrom, and curved from the lower corner end to the upper corner end diagonally, so as to fit close around the side of the cylinder. Thus, as the cylinder is being turned, these cutters will scoop up the dirt in such a manner that all of it will be retained therein until the cylinder is full enough to be emptied of it.

The cutters being secured by bolts and screw-nuts *h* enables them to be detached and sharpened when dull.

Having thus fully described my invention,

What I claim therein as new, and desire to secure by Letters Patent, is—

The detachable curved cutters *g*, when arranged at an incline on the inside of the cylinder, in combination with the plates or braces *e e*, substantially in the manner and for the purpose as herein shown and described.

As evidence that I claim the foregoing as my invention, I have hereunto set my hand in the presence of two witnesses.

SAMPSON POPE.
